VALVE LIFTER FOR DIESEL MOTORS

Lawrence E. Moore, 2616 Harvard Ave., Roseburg, Oreg.

Filed June 7, 1954, Ser. No. 434,813

2 Claims. (Cl. 29—219)

This invention relates generally to heavy duty internal combustion motors and particularly to a valve lifter for diesel motors.

The main object of this invention is to facilitate the lifting of heavy duty motor valves for repair purposes.

The second object is to make the removal of the valves a one man job, which one man can perform in less time than is ordinarily required for two men and without danger to the fingers of the operator.

The third object is to so construct the lifter that it can be used on a wide variety of styles and types of diesel motors.

I accomplish these and other objects in the manner set forth in the following specification as illustrated in the accompanying drawing, in which:

Figure 1 is a side elevation showing a portion of the device and a portion of a valve head broken away in section.

Fig. 2 is a section taken along the line 2—2 in Fig. 1.

Fig. 3 is a section taken along the line 3—3 in Fig. 1.

Fig. 4 is a section taken along the line 4—4 in Fig. 2.

Fig. 5 is a perspective of the adapter shown in Fig. 1.

Referring in detail to the drawing, there is shown a valve head 10 in which is formed a valve seat 11 for a disc valve 12 whose stem 13 extends through a bushing 14 in the head 10. On the stem 13 above the face 15 is a compression spring 16, it being understood that the valve 12 and associated parts are in multiple to correspond to the number of valves to be lifted.

It will be understood that each stem 13 is provided with a reduced end portion 17 for the conventional washer 18 which normally occupies a recess 19 in the spring cap 20 into which extends the upper end of a spring 16.

Referring particularly to my invention, same will be seen to include a base plate 21 having a boss 22 on its under side through which extends a hold down bolt 23 by means of which the plate 21 can be rigidly mounted on the face 15 by mounting the bolt 23 in the tapped hole 24 in the face 15.

On the plate 21 is mounted an adapter (Fig. 5) comprised of a plate 25 having a tapped hole 26 for a clamping bolt 27 whose head is on the underside of the plate 21.

On the plate 25 is a tubular socket 28 adapted to receive a standard 29 which may be secured to the socket 28 by a pin 30, preferably secured by a cotter pin 31. 60 Various holes 32 may be provided along the standard 29 to provide a quick change in the setting beyond the range of the turnbuckle unit which will be described.

On the standard 29 is slidably mounted the cross slide 33 provided with rollers 34 to reduce friction. Attached to the slide 33 is a pusher plate 35 having holes 36 formed therein to receive the washers 18 of a given group of valves. The top side of each hole 36 is provided with a countersink 37 to facilitate the removal of the washer 18.

The plate 35 is attached to the slide 33 by means of

2

a bolt 38 which is tapped into the plate 35. Attached to the slide 33, by means of a pin 39, is the lower rod 40 of a turnbuckle whose nut 41 is joined to the upper rod 42 which is joined by a pin 43 to an overthrow lever 44 whose end 45 is joined by a pin 46 to an ear 47 formed on the upper end of the standard 29. The lever 44 has a socket 48 into which may be inserted a handle 49.

The operation of the lifter is as follows: Assuming that the parts are in the position shown in Fig. 1 and it is desired to remove the valves 12, all that is needed is to depress the lever 49 which will cause the plate 35 to be depressed as shown in Fig. 4 and cause the lever 49 itself to be held in a locked depressed position, in which the valve lock washer 18 may be inserted or removed with a minimum of effort or danger.

Obviously, to release the lifter, it is only necessary to raise the handle 49 past its locking center and restore it to the position shown in Fig. 1.

I claim:

20 1. A valve spring compressor for overhead valves comprising an elongated horizontal base plate, a boss on the under side of one end of said base plate, a hold down bolt through said base plate and boss, a vertical socket on the top side of the opposite end of said base plate, an upright standard in said socket, said socket and standard having transverse apertures receiving a pin to secure the standard in the socket, a slide projecting from one side of said standard parallel with and overhanging said base plate, rollers on said slide engaging opposite sides 30 of said standard, a pusher plate on said slide adapted to engage valve springs on opposite sides of said slide, a hand lever hinged to said one side of said standard and extending over said slide, and a push rod having fine length adjustment pivotally connected between said slide and hand lever to depress said pusher plate.

2. A valve spring compressor for depressing a group of springs of overhead valves projecting upwardly from a valve head comprising an elongated base plate having a hold-down bolt in one end thereof for securing the base plate in horizontal position against the top of the valve head between said springs, a vertical upright standard secured on the opposite end of said base plate, a horizontal slide extending over said base plate from one side of said standard, rollers on said slide engaging opposite sides of said standard to provide for vertical movement of said slide on said standard, a pusher plate on said slide adapted to engage the upper ends of said valve springs on opposite sides of said slide, a hand lever hinged to said one side of said standard and extending over said slide, and a push rod having turnbuckle length adjustment pivotally connected between said slide and hand lever to depress said pusher plate, said push rod and hand lever forming a self-locking toggle joint when said hand lever is depressed.
